US00D403432S

United States Patent [19]

Geysen et al.

[11] Patent Number: Des. 403,432

[45] Date of Patent: **Dec. 29, 1998

[54] **MULTIPLE CHEMICAL REACTION WELL SHEET**

[75] Inventors: **H. Mario Geysen; Michael Green**, both of Chapel Hill, N.C.

[73] Assignee: **Glaxo Wellcome Inc.**, Research Triangle Park, N.C.

[**] Term: **14 Years**

[21] Appl. No.: **50,265**

[22] Filed: **Feb. 13, 1996**

[51] LOC (6) Cl. **24-01**

[52] U.S. Cl. **D24/225**

[58] Field of Search **D24/226, 227, D24/229, 230, 216, 225, 223; 436/6; 422/52, 56, 68.1, 61, 65, 102**

CLAIM

We claim the ornamental design for a multiple chemical reaction well sheet, as shown and described.

DESCRIPTION

FIG. 1 is a top plan view of the multiple chemical reaction well sheet, showing our new design;

FIG. 2 is a bottom plan view thereof;

FIG. 3 is perspective view thereof;

FIG. 4 is a front elevational view thereof;

FIG. 5 is a rear elevation view thereof; and,

FIG. 6 is a side elevation view thereof.
